LOCOMOTIVE STRUCTURE

Harry M. Pflager, St. Louis, Mo., assignor to General Steel Castings Corporation, Granite City, Ill., a corporation of Delaware

Application March 28, 1932. Serial No. 601,465

15 Claims. (Cl. 105—44)

The invention relates to railway rolling stock and consists in a novel locomotive underframe and associated structure.

It has been customary heretofore to mount the air brake operating cylinders at the rear of the main steam cylinder saddle and in order to accommodate these cylinders substantial spaces were necessary in the framing at the rear of the saddle. In a familiar type of cast locomotive bed, an underframe backbone member of box cross section is utilized to provide a strong rigid structure and the usual cylinder arrangement necessitated cutting away this backbone member adjacent to the brake cylinders and the steam cylinder saddle where increased rigidity was desirable.

In locomotives having two-wheel front engine trucks, the space between the front drivers and the cylinder saddle is so restricted that it is difficult to apply the brake cylinders and associated gearing in the usual position.

The main object of the present invention is to overcome the disadvantages set forth above, and this object is accomplished by locating the brake cylinders in front of the cylinder saddle and extending brake operating rods through the saddle. This arrangement makes possible continuing the backbone member up to and preferably merging with the rear portion of the saddle structure and affords ample room for mounting, operating, inspecting and repairing the brake cylinder and associated gearing. Preferably the structure described is to be formed integrally by casting or otherwise, and locating the air brake cylinders in front of the saddle is advantageous in such integral construction as these parts are more accessible for machining, bushing, etc.

In the accompanying drawings illustrating a preferred embodiment of the invention—

Figure 1 is a top view of one longitudinal half of the forward portion of a locomotive bed with associated brake gearing.

Figure 2 is a side view, a portion of the bed being sectioned adjacent to the brake pull rod.

Figure 3 is a half front elevation of the structure shown in Figures 1 and 2.

Figures 4, 5 and 6 are vertical transverse sections taken on the corresponding section lines of Figures 1 and 2.

The main steam cylinders and their supply chambers are indicated at 1 and 2, respectively, and are shown as being cast integrally with the cylinder carrying saddle which includes side walls 3, transverse walls 4 and 5, a lower wall 6, an upper wall 7, a boiler supporting member 8,

exhaust steam passageways 9 and longitudinal webs 10.

The underframe includes a main backbone portion of box section (see Figure 6) including side walls 11, bottom wall 12 and top wall 13, 60 and this box section merges with the rear portion of the cylinder saddle. Supplementary side members indicated at 14 are utilized to form the driver pedestals 15. A box shaped front deck structure 16 extends forwardly from the cylinder 65 saddle and terminates in an end sill 17. Walls 18 extend upwardly from the deck and form supporting structure for the usual water and air pump cylinders (not shown). Members 18 are braced by deep transverse webs 19 and 19a. 70

Preferably air brake operating cylinders 20 are cast integrally with the front deck structure, the transverse web 19a having openings 21 for cylinders 20.

A yoke 22 is attached to each cylinder piston 75 rod 23 and links 24 extend along each side of the cylinder to the rear thereof where they are connected by a bar 25 to which a pull rod 26 is attached. Pull rods 26 extend through suitable openings provided in saddle walls 4 and 5 and 80 extend lengthwise and interiorly of the backbone member to a point where they may be connected to brake levers 27. The brake shoes are applied to the drivers 28 by means of levers 27 and associated gearing 29. 85

The wheels 30 indicate a four-wheel front truck which tends to space the front drivers 28 from the main steam cylinder 1, and cylinder saddle, a greater distance than would be present if a two-wheel engine truck is utilized, in which 90 case the wheels would be in front of the steam cylinders and the drivers would be so close to the saddle that it would be difficult to locate a brake cylinder at the rear of the saddle.

It is not essential to the invention that the 95 locomotive underframe be a one-piece cast bed or that the brake cylinder be cast integral with the front deck structure. Various other details illustrated and described may be varied without departing from the spirit of the invention. I 100 contemplate the exclusive use of those features of the invention which come within the scope of the claims irrespective of modifications in details.

What is claimed is:

1. In a locomotive, a main steam cylinder saddle, and a brake operating cylinder carried in front of said saddle.
2. In a locomotive, a main steam cylinder saddle, a brake operating cylinder carried in front 110

- of said saddle, and brake lever operating rods extending from said brake cylinder through said saddle.
3. In a locomotive, a front deck framing structure and a brake cylinder carried thereby.
4. A locomotive front deck structure having a brake cylinder body integral therewith.
5. In a locomotive bed, a main steam cylinder saddle, framing members projecting forwardly therefrom, and a brake cylinder body carried by said members, all of said parts comprising an integral structure.
6. In a locomotive bed, a steam cylinder saddle, a backbone member of box section extending rearwardly of said saddle and merging therewith and a brake operating cylinder located in front of said saddle.
7. In a locomotive bed, a cylinder saddle, a backbone member extending rearwardly of said saddle and merging therewith and elements in front of said saddle for supporting a brake operating cylinder.
8. In a locomotive, a bed as specified in claim 6, and brake operating gear extending from said brake cylinder through said saddle and member.
9. As a new article of manufacture, a locomotive bed integral structure comprising a saddle for carrying a main steam cylinder, a brake operating cylinder body in front of said saddle, and a main backbone member of box section merging with the rear portion of said saddle.
10. A structure as specified in claim 9 which also includes a main steam cylinder as an integral part thereof.
11. In a locomotive, a main steam cylinder saddle, a front deck, a brake cylinder carried on
- said deck with a piston rod projecting outwardly therefrom towards the front end of the locomotive, a brake lever pull rod extending through said saddle and means connecting the forward end of said pull rod with the outer end of said piston rod.
12. In a locomotive, a main steam cylinder saddle, a front deck, a brake cylinder carried on said deck, a piston rod projecting outwardly from said cylinder towards the front end of the locomotive, a yoke on said piston rod, links at the sides of said cylinder connected to said yoke, a bar between said links at the rear of said cylinder, and a brake lever operating rod connected to said bar and extending through said saddle.
13. In a locomotive, a main steam cylinder saddle, a front deck, upright longitudinal walls at the sides of said deck for mounting air and water pumps, a transverse web between and bracing said walls, there being an opening in said web, and a brake cylinder carried on said deck and projecting through said opening.
14. In a locomotive as specified in claim 13, a piston rod projecting from the end of said cylinder in front of said transverse web, a brake operating pull rod extending through said saddle, and means extending through said web and connecting said piston rod and pull rod.
15. In a locomotive bed, a saddle near one end thereof for carrying a main steam cylinder, a backbone member of box section extending from said saddle towards the other end of the bed, and a brake operating cylinder element between said saddle and said first-mentioned end.
